OTHO FULTON, OF SUNDRIDGE PARK, BROMLEY, ENGLAND

ELECTRICAL TRANSMISSION OF PICTURES

Application filed October 3, 1928, Serial No. 310,002, and in Austria October 13, 1927.

For transmitting a picture or a drawing or the like to a distance, it is necessary to decompose the whole picture surface into points or elements and in some way or other to impress upon a train of waves being transmitted the tone value of each point or element of the picture in succession. This may be done in either of two ways. Either a signal of varying intensity, or a series of current impulses 10 of uniform intensity but varying duration may be transmitted. It is with the latter method that the present invention is concerned.

The invention is particularly, though not exclusively, applicable to a system in which current impulses corresponding to the picture elements are used to modulate a carrier wave of audio-frequency and this modulated wave of audio-frequency is utilized in its turn to 20 modulate a carrier-wave of radio-frequency. Where the current impulses corresponding to the tone values of the several elements of the picture are used to modulate an alternating current, the frequency of the latter must be 25 very high compared with that of the impulses if the tone values are to be correctly reproduced. This is especially so in the case of half-tone pictures in which the transmitting apparatus comprises a conducting foil 30 upon which the picture is represented by lines of insulating material. In this case the current will in the ordinary way have a very sudden rise and fall.

More particularly in the case of high picture frequencies, considerable difficulties occur in the amplification on account of the inductive resistances and capacity values which are particularly troublesome. Faults occur such as omission of half tones, subsequent 35 action after the signal impulses, which faults, in the case of half-tone pictures may lead to complete wiping out in the case of line drawings or the like, to the appearance of double outlines or even of white spaces along the 40 lines.

By means of the invention, the amplification absolutely necessary for the practical transmission of pictures and modulation of the transmitter or the like can be obtained even at the highest picture frequencies used. 50

The completely correct reproduction of short impulses of voltage or current is exceedingly difficult since capacities and inductances exercise a very great influence and must be taken into account in building any 55 amplifier arrangement. Indeed, in the case of currents with a very square wave form it is impossible to construct, in such a way as to avoid distortion, the various devices through which the picture currents have to 60 pass before being radiated from the transmitter. In addition, it is desirable to avoid the necessity for apparatus at the receiving end designed specially to deal with impulses of square wave form. 65

According to the present invention, a system for the transmission of pictures and other transmissions, in which the tone values of picture elements are represented by current impulses having a sudden rise and fall, is 70 provided with means for retarding the rate of change of said impulses.

Such a system preferably comprises a source of current (such as a battery) electrically connected in series with a picture exploring means, a resistance, and a further resistance shunted by a condenser, for the purpose of producing, across the condenser, impulses of voltage whose rise and fall is comparatively gradual. 75

The picture exploring means will in this case consist of some means of exploring successively the points or elements of the picture constituting a device the electrical properties of which change suddenly as the picture is transmitted. It may for instance comprise a rotating drum of conducting material upon which is stretched a copper foil upon which the picture is represented by lines of insulating material of varying width corre- 85 90 95

sponding to the tone values of the picture elements and a conducting stylus which slowly traverses the drum lengthwise. It will be realized that as the drum rotates, the electrical resistance to a current flowing between the stylus and the drum changes almost instantaneously.

Such current impulses (converted, for example, into gradual voltage changes as described) may be caused to modulate a carrier-wave so that the building up and dying away of such modulated carrier-wave takes place comparatively gradually.

Means is preferably provided for varying at will the characteristics of the gradual rise and fall of voltage or current, whether direct or alternating, so as to vary the character of the picture received. Thus, it is possible to adjust the values of capacity, resistance or inductance in the circuit so that in the case of short current impulses the maximum current value is never reached.

The result is that the gradation of the tone values of the pictures received can be arranged in the most favorable manner for each individual case. For instance, pictures otherwise unsuitable for transmission, that is to say, extremely hard or extremely soft, can be received at the receiving end with correct tone reproduction. This variability at will of the tone reproduction of pictures is a desirable by-effect, the chief advantage, however, is the possibility given for the first time by the arrangement mentioned, of ensuring the passage, without disturbance, of picture currents in the ordinary way, without any special arrangements at the transmitting or at the receiving end.

The current impulses conveniently be caused to produce comparatively gradual corresponding changes of the potential of a grid of a mixing valve, to the anode circuit of which is supplied an auxiliary carrier-wave of audio-frequency, and from the anode circuit of which it is taken after modulation.

The control of the auxiliary frequency utilized as the carrier for the picture frequency, by the direct current impulse controlled in accordance with the above process, takes place in a mixing valve connection. These direct current impulses are supplied to the controlling electrode or electrodes of the three or more electrode valve used as the mixing valve, and the auxiliary frequency to be controlled and that already cancelled, is supplied to, or taken from, circuits which are connected to the other electrodes of the mixing valve.

A construction in connection with a simple 60 feeler device is shown in the drawing, the picture being decomposed for instance into conducting and non-conducting screen lines.

The auxiliary frequency used is brought through the transformer T1 into the anode 65 circuit of the mixing valve. If the feeler

pencil is at A on an insulating screen line, the battery B2 will produce through the resistance R2 such a negative voltage that the alternating voltage existing between the anode and cathode, will be compensated. If 70 the contact is closed at A, the battery B1 will generate through the resistance R1 in the resistance R2 such a voltage of opposite potential that it will be possible to take through the transformer T2 from the anode circuit 75 an alternating voltage of the auxiliary frequency used, which can be further utilized for instance for the modulation of a wireless transmitter. When the contact in A is opened or closed, the above mentioned changes of voltage of the control electrode of the mixing valve will not take place instantaneously, but in accordance with the charging or discharge curve of the condenser C which can be controlled at will by the resistances R1 and R2 and the value of the capacity C.

The nature and scope of the invention having been thus indicated and its preferred embodiment having been specifically described, 90 what is claimed as new is:

1. In a system for the transmission of pictures or other representations, the combination of a transmitting circuit comprising a picture exploring means and a source of electric current connected in series therewith for producing current impulses having a sudden rise and fall and representing the tone values of the picture, and a condenser also electrically connected in said circuit so as to reduce the rate of change of said impulses.

2. In a system for the transmission of pictures or other representations, the combination of a transmitting circuit comprising a picture exploring means and a source of electric current connected in series therewith for producing current impulses having a sudden rise and fall and representing the tone values of the picture, and a condenser also connected in said circuit for reducing the abruptness of said impulses and a resistance in series with the condenser.

3. In a system for the transmission of pictures or other representations, the combination of a transmitting circuit comprising a picture exploring means and a source of electric current connected in series therewith for producing current impulses having a sudden rise and fall and representing the tone values of the picture, and a condenser also connected in said circuit, a resistance in series with said condenser and with said exploring means and a further resistance in parallel with the said condenser.

4. In a system for the transmission of pictures or other representations, the combination of a transmitting circuit comprising a picture exploring means and a source of electric current connected in series therewith for producing current impulses having a sudden

rise and fall and representing the tone values of the picture, and a condenser also connected in said circuit, a resistance in series with said condenser and with said exploring means 5 and a further resistance in parallel with the said condenser, and a thermionic valve having its input side connected across the said condenser, means for introducing a carrier wave into a circuit containing the output side 10 of the thermionic valve and means for drawing the modulated energy from the said output circuit.
